UNITED STATES PATENT OFFICE.

LOUIS HERMAN CREEKMORE, OF BRISTOW, OKLAHOMA.

COTTON-PICKER.

1,139,492.

Specification of Letters Patent. Patented May 18, 1915.

Application filed August 3, 1914. Serial No. 854,786.

To all whom it may concern:

Be it known that I, LOUIS HERMAN CREEKMORE, a citizen of the United States, residing at Bristow, in the county of Creek and State of Oklahoma, have invented certain new and useful Improvements in Cotton-Pickers; and I do declare the following to be a full, clear, and exact description of the invention, such as will enable others skilled in the art to which it appertains to make and use the same.

My invention relates to improvements in cotton picking machines and has for its object to improve the construction of devices of this character to such an extent as to provide an extremely simple yet highly efficient machine which will readily perform the functions for which it is designed.

In carrying out the above end, the invention aims to provide a new and novel valve structure in connection with a suction tube having a picking nozzle and a discharge chute therefrom.

The invention also aims to provide a new and novel form of picking head whereby the cotton may be removed from the top and sides of the plants simultaneously.

With the above and minor objects in view, the invention resides in certain novel features of construction and combination herein described and claimed and shown in the drawings wherein—

Figure 1 is a side elevation of a cotton picker constructed in accordance with my invention; Fig. 2 is a vertical longitudinal section through the entire device; Fig. 3 is an end view; Fig. 4 is a transverse section taken on the line 4—4 of Fig. 1.

In the embodiment illustrated and in the accompanying drawings, a supporting platform P is shown which is provided with suitable wheels W and with a tongue at its rear end whereby the running gear, thus formed, may be propelled forwardly.

Rising from the front end of the platform is an inverted U-shaped frame 1 upon the cross bar 2 of which a tubular elbow 3 is secured by means of a band 4 or other suitable means; the lower end of the elbow 3 is being flexibly connected, preferably by a leather joint 5, with a pipe section 6 in which a second section 7 slides, the lower

end of the pipe 7 being reduced in size as indicated at 8 whereby to provide a sucking nozzle adapted to remove cotton from the tops of the plants. At the juncture of the reduced portion 8 with the body of the pipe 7, a pair of picking tubes 9 are provided whose lower ends are adapted to be positioned adjacent the sides of the cotton plants whereby, when suction is created within the tube 7, any cotton upon the tops and sides of the plants will be drawn inwardly through the reduced portion 8 and the tubes 9.

For the purpose of retaining the pipe section 7 in any one of its adjusted positions, a pair of weights 10 are preferably provided which are secured to one end of cables or chains 11, the latter passing over sheaves 12 or guides 12 at the upper corners of the frame 1 and being secured at their opposite ends to the section 7 as indicated at 13. By this means, the weight of the tube 7 and the parts carried thereby is practically balanced. From the other end of the elbow 3, a suction tube 14 extends rearwardly, the intermediate portion of said tube being supported by an inverted V-shaped bracing member 15 whose lower ends are secured to the forward upright side 17 of a cotton receiving hopper, a second upright wall 18 extending transversely above the platform P and lying parallel to the wall 17 and two end walls 19 being also provided, the latter being hinged to the walls 17 and 18 by pairs of pins 20 projecting from the upper corners of said walls 19 through the adjacent upper corners of said walls 17 and 18, whereby they may be swung outwardly for the purpose of removing the cotton deposited in the bin or hopper.

As clearly seen in the various figures of the drawings, the extreme rear end of the suction tube 14 communicates with the forwardly turned upper end 21 of a discharge chute 22 which is preferably though not necessarily rectangular in horizontal section. The lower ends of the side walls 23, of the chute 22, are cut in such a manner as to cause their front and rear edges to converge downwardly, thus forming pointed lower ends 24 for said side walls, while the end walls 25 of said chute terminate at the

juncture of the triangular ends 24 with the sides 23.

To the lower ends of the end walls 25, a pair of rectangular frames 26 are hinged as at 27 and normally forced inwardly by means of light leaf springs 28, said frames 26 being secured to the edge of flexible sheets 29 which are preferably formed of leather, the tension of the springs 28 acting to normally force the sheets 29 against the inclined edges of the pointed ends 24 whereby the lower end of the chute 22 is normally closed. It will be noted by reference to the drawings, that the sheets 29 and the frames carrying the same are located directly above the bin or hopper and that said sheets 29 constitute valves in a manner to be more clearly set forth.

Mounted upon the rear end portion of the platform P, is a suction fan 30 which is normally driven by a belt 31 leading from the fly wheel of an engine 32 likewise mounted upon the rear portion of said platform. From the fan 30 a suction tube 33 leads to the upper end of the rear side wall of the chute 22, with which said tube communicates, an upright screen 34 being provided to prevent the passage of cotton into said tube 33.

30 With the parts as above described, the gasoline engine or motor is set in motion to drive the fan 30 which now creates a suction directly through the tubes 8 and 9, through the instrumentality of the tube sections 6 and 7, the elbow 3 and the suction tubes 14 and 33. During this operation, the lower end of the chute 22 is closed by the leather valve sheets 29, the result being that when the machine is propelled forwardly and the picking head, including the tubes 8 and 9, properly positioned in respect to the rows of cotton, the cotton will be drawn inwardly from the plants and, on account of the fact that the screen 34 checks the movement of the cotton toward the fan 30, the same will be forced to fall into the chute 22 and to rest upon the sheets 29. Said sheets will assume their normally closed position until the weight of the cotton in the chute 22 is sufficient to overcome the amount of suction in the upper end of the chute and the tension of the springs 28, whereupon said sheets and their frames will swing around their hinges 27 against the tension of the springs 28 and will discharge an amount of cotton into the hopper, after which the tension of said springs and the suction in the upper end of the chute will again close the sheets 29 until more cotton has accumulated above the same, at which stage, the above explained operation again takes place.

From the above description, taken in connection with the accompanying drawings, it will be seen that I have produced new and novel means for allowing suction to be

created in the picking tubes and that this means also provides for the discharge of cotton from the chute 22 at spaced intervals, that new and novel means have been provided whereby the movable pipe section 7 may be supported in any one of a number of positions and that I have likewise improved the construction of the picking head.

I may here explain that the fact that the cotton is discharged from the chute 22 at spaced intervals is an important feature of the invention; since, if it becomes inexpedient to employ the bin or hopper, suitable sacks (not shown) may be provided into which the cotton may be discharged, it being readily seen that a new sack could well be provided for receiving each body of cotton discharged. In most cases, however, the bin or hopper suffices and is so constructed as to allow the cotton to be readily removed therefrom.

I have described my invention with considerable detail, but I do not wish to be limited to features of construction or arrangement and proportioning of parts otherwise than as set forth in the appended claims.

Having thus described my invention, what I claim as new and desire to secure by Letters-Patent is—

1. A cotton picker comprising a suction tube, a screen therein, an imperforate four sided discharge chute depending from the tube in advance of the screen and communicating with the interior of the former, two of the opposite side walls of said chute being V-shaped at their lower ends, and a pair of valve members contacting with the inclined edges of said side walls and hinged at their upper edges to the lower ends of the other two walls, said members being normally closed by the suction within the tube and being designed to be opened by the weight of cotton accumulating above the same.

2. In a device of the character described, an upright suction tube having its lower end reduced to provide a suction nozzle, and a pair of substantially C-shaped branch pipes secured at their upper ends to opposite sides of said pipe above the reduction therein and opening thereto, the upper ends of said pipes facing each other and the lower ends thereof likewise facing each other and being spaced below said reduced end of the tube.

3. A cotton picker comprising a suction tube, a screen therein, an imperforate four sided discharge chute depending from the tube in advance of the screen and communicating with the interior of the former, two of the opposite side walls of said chute having V-shaped lower ends depending below the lower ends of the other two walls, a pair of rectangular frames hinged at their upper sides to said lower ends of the last-named

walls, flexible sheets secured to the inner sides of said frames, and springs for normally forcing said frames inwardly to cause the sheets thereon to contact with said V-shaped ends, whereby the lower end of the 5 chute may be normally made air tight, for the purpose set forth.

In testimony whereof I have hereunto set my hand in presence of two subscribing witnesses.

LOUIS HERMAN CREEKMORE.
